United States Patent Office

Des. 222,034
Patented Sept. 28, 1971

222,034

COMBINED BOTTLE AND BASE THEREFOR

Bjorn Bagn, New Hartford, Conn., assignor to Emhart Corporation, Bloomfield, Conn.

Filed July 28, 1970, Ser. No. 24,193

Term of patent 14 years

Int. Cl. D9—01

U.S. Cl. D9—12

FIG.1

FIG.3

FIG. 1 is a top plan view of a combined bottle and base therefor showing my new design;

FIG. 2 is a side elevational view;

FIG. 3 is a bottom plan view; and

FIG. 4 is a fragmentary sectional view taken through the base and lower portion of the bottle.

I claim:

The ornamental design for a combined bottle and base therefor, as shown and described.
